UNITED STATES PATENT OFFICE.

ROBERT E. BURNS, OF SAN FRANCISCO, CALIFORNIA.

FRUIT-DRIER.

SPECIFICATION forming part of Letters Patent No. 268,619, dated December 5, 1882.

Application filed June 8, 1882. (No model.)

To all whom it may concern:

Be it known that I, ROBERT E. BURNS, a citizen of the United States, and residing at San Francisco, in the county of San Francisco and State of California, have invented certain new and useful Improvements in Fruit-Driers, of which the following is a specification.

My invention relates to certain new and useful improvements upon the machines or fruit-driers for which Letters Patent of the United States were granted to me on the 9th day of November, A. D. 1880, No. 234,115, and also on the 27th day of December, A. D. 1881, No. 251,408; and the objects of my present improvements are, first, to provide an improved arrangement of the drying-chambers and the means for regulating the temperature therein; second, to provide a means whereby the waste heat from the lye-pot furnace may be utilized 20 for the defecation of fruit; and, third, to provide certain auxiliary drying-compartments, frames, or trays, whereby the residue or surplus heat from the primary drying-compartments may be utilized and the drying capacity of the 25 machine or apparatus greatly increased. These objects I accomplish by the device illustrated in the accompanying drawings, in which—

Figure 1 is a perspective view of my improved machine. Fig. 2 is a ground plan. 30 Fig. 3 is a vertical sectional view of the lye-pot and its furnace. Fig. 4 is a longitudinal vertical section through the main drying-chamber. Fig. 5 is a transverse vertical section through the same.

Similar letters of reference are used to designate like parts throughout the several views.

A is a rectangular furnace, provided with the usual door and draft openings in front and with cold-air openings B B through the side 40 walls.

The combustion-chamber C consists of a rectangular box of sheet-iron, which fits within the walls of the furnace-chamber and is provided with a return-flue, D. The flames and products of combustion enter the return-flue at its rear end, and pass out at its front end, and enter the double flue E, travel toward the rear end of the furnace-chamber and enter an auxiliary or fume chamber, Q, extending at right 50 angles across the end of the furnace-chamber, and having at one end a smoke-stack, R.

At one side of the furnace-chamber A, I con-

struct a second chamber, F, of like dimensions as the first, and at the front end of this secondary chamber I build the lye-pot furnace G, 55 having a fire-door in front and a smoke-flue in the rear, connected with the pipe H, leading to the combustion-chamber C, and having a damper or valve, I.

The exit-pipe of the double flue E is also 60 provided with a damper, J.

Around the top of the furnace-wall a ledge is formed to support a tray, K, filled with mortar or cement, and having a number of openings, L, controlled by dampers or slides M. 65 These openings are placed beneath the center of each drying compartment or chamber N.

Over each opening L, I place a deflecting plate or tray, K', made of metal and filled with cement, and mounted upon legs resting on 70 the mortar filling of the tray K.

The drying-chambers N are constructed similar to those described in my before-mentioned Letters Patent No. 251,408, with this exception, that the opening or passage O for the 75 moisture-laden heated air is opened or closed by drawing forward or sliding back the fruit-tray immediately below the air-tight finishing-chamber P. The air-passages O communicate with a flue, S, situated to the rear of the finishing-chamber and discharging into the steam-box T, provided with a chimney, U, and attached to the rear of the main drier by means of clips, and supported by legs V, resting on 80 the top of the auxiliary drying-chamber Q. 85

Ventilating-doors W may be placed on the roof of the main drier, as shown in Fig. 1, and short posts X should be placed on the roof to support a large drying-frame, Y, the edges of which overhang the face-walls of the main 90 drier, so as to catch and utilize all escaping and radiated heat, which in all other driers is lost.

If desirable, a skylight may be placed over the large drying-frame Y, and the natural heat 95 of the sun be used to assist the artificial heat.

When a fire is built in the furnace G the resultant smoke and a great portion of the heat will pass through the pipe H and enter the combustion-chamber C, thereby increasing the 100 heating capacity of the main furnace, and at the same time warming the chamber F with heat radiated from the said pipe H. Should this degree of heat not be sufficient, then the

slide of the air-passage Z in the wall of the main furnace may be drawn back and heat from the main furnace or combustion chamber be admitted. The heat arising from the furnace-chambers passes up through the openings L and out under the deflecting-plate K', and passes upward on all sides of the wooden or lower tray, a, and from thence passes upward to the top of the drying-chamber, being deflected from side to side and from front to rear in the manner already described in my before-mentioned Letters Patent No. 251,408. The moisture-laden heat, after passing out into the flue S, enters the steam-box T, and by imparting considerable warmth to it I am enabled to dry any fruit that may be placed thereon. Should there be any gases, fumes, or overplus of heat received into the said steam-box, they will find an exit through the chimney U. The products of combustion from the main furnace, together with those from the lye-pot furnace, pass through the double flue E into the conducting-pipe b and enter the fume-chamber Q, its entrance or flow being regulated by the damper or slide J, and by raising the temperature in said chamber accelerates the drying of fruit placed in or on trays laid upon the top or roof of the chamber Q. The residue of heat and smoke passes up through the smoke-stack R and escapes into the open air.

Having thus described my invention, what I claim, and desire to secure by Letters Patent, is—

1. In a fruit-drier, the combination of the combustion-chamber C, having a return-flue, D, communicating with a double pipe, E, discharging into an auxiliary fume-chamber, Q, substantially as shown and described.

2. In a fruit-drier, the combination, with the main furnace or combustion chamber C, of the lye-pot furnace G and connecting-pipe H, hav-

ing damper I, and discharging into the combustion-chamber, substantially as shown and described.

3. In a fruit-drier, the combination of the main chamber A, having combustion-chamber C, communicating with the double pipe E by means of the return-flue D, the connecting-pipe b, having damper J, and the auxiliary drying-chamber Q, provided with smoke-stack R, substantially as shown and described.

4. In a fruit-drier, in combination with the main furnace and drying chambers thereof, the secondary or duplicate chamber F, lye-pot furnace G, pipe H, and air-passage Z, substantially as shown and described.

5. In a fruit-drier, the combination of the damp air-passages O, located at the top of the main drying-chamber N, the flue S, situated below and to the rear of the finishing-chamber, 60 and the steam-box T, provided with pipe or chimney U, substantially as specified.

6. In combination with a fruit-drier constructed as shown and described, the overhanging screen or tray Y, placed upon suitable supports above the roof of said drier, substantially as and for the purpose set forth and specified.

7. In a fruit-drier, the combination of the main furnace and drying chambers, the secondary or duplicate furnace and drying chamber, the finishing-chamber, and the overhanging screen or tray, substantially as shown and described.

In testimony that I claim the foregoing I have hereunto set my hand and seal this 10th day of May, 1882.

ROBERT E. BURNS. [L. S.]
